(57) **CLAIM**

The ornamental design for a blossom shaped silicone bearing, as shown and described.

DESCRIPTION

FIG. 1 is a perspective view of a blossom shaped silicone bearing;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines show portions of the blossom shaped silicone bearing that form no part of the claimed design. The dash-dot broken lines are for the purpose of showing the bounds of the claimed design, and form no part thereof.
